Des. 206,282
Patented Nov. 22, 1966

206,282

HAND GREASE GUN

Edwin P. Sundholm, Albert City, Iowa 50510

Filed Mar. 2, 1966, Ser. No. 1,240

Term of patent 14 years

(Cl. D46—1)

Fig. 1.

Fig. 2.

FIG. 1 is a top plan view of the hand grease gun embodying my new design;

FIG. 2 is a side-elevational view taken from the bottom of FIG. 1;

FIG. 3 is a side-elevational view taken from the left of FIG. 2;

FIG. 4 is a side-elevational view taken from the right of FIG. 2; and

FIG. 5 is a bottom view of the same grease gun.

I claim:

The ornamental design for a hand grease gun, as shown.
